BRASSIÈRE

Hilde Holister, Berlin, Germany, assignor to Ella Miller, Berlin, Germany

Application October 14, 1936, Serial No. 105,609
Renewed April 6, 1939

1 Claim. (Cl. 2—42)

This invention relates to brassières for supporting and molding the breast, of that type in which a pair of breast supports are connected at their front ends and supported by shoulder straps through the medium of bands arranged in the shape of the inverted letter V and clearing the nipples.

It is an object of the invention to provide an improved brassière of the type described.

To this end, more than one pair of the aforesaid V bands are arranged at the front end of each shoulder strap, to improve the molding action of the brassière, an elastic member is attached to the rear end of one of the supports and anchored to a girdle, another elastic member is attached to the rear end of the other support and mounted to slide on the anchored member, and the rear ends of the shoulder straps are connected to the elastic members at points intermediate the ends of the members.

By these means, on the one hand, the breasts are molded more efficiently to improve a flat bust and to restrain too full a bust, and, on the other hand, the brassière, while held reliably in position, opposes a minimum resistance to the wearer's movements.

A brassière embodying the invention is illustrated by way of example in the accompanying drawing, in which:

Fig. 1 shows a breast support in front elevation.

Fig. 2 is a rear elevation of Fig. 1.

Referring now to the drawing, the brassière comprises on the front side (Fig. 1) two supports 2, 3 united by a foundation band at their lower sides 4 and made of textile material or other suitable fabric, each support having a semicircular cut-out portion 4 forming apertures for the front portions of the breasts 24, with the nipples 25. The two supports 2 and 3 form at their upper sides a wedge-shaped gap 5 which allows the supports 2, 3 to be approached more or less, if necessary, by some suitable means such as a loop 6 and a button 7, thereby varying the width of the gap.

The apertures formed by the cut out portions 4 are considerably larger than the diameter of the breast nipples and allow the front portion of the breast to protrude unimpeded and without discomfort. Thus, this portion of the breast is protected against pressure and covered only by the clothes in a perfectly hygienic manner.

Wedge shaped portions a, b extend to the rear of the supports 2 and 3 and are passed under the arm pits 8 to the back. The rear portions a and

b are connected by elastic means anchored to a girdle 12 and supporting the rear ends of the shoulder straps 18, as follows: A loop 9 of elastic material, rubber band or the like, is attached to the rear end of the portion b, and the eye 10 of the loop is secured to a button 11 on the girdle 12. This loop is threaded through the eye 13 of a similar loop 9' attached to the rear end of the portion a, and makes a sliding connection of the loops, so that the supports 2 and 3 are elastically connected to each other, and anchored elastically to the girdle 12, and the loops 9, 9' are free to move with respect to each other. The rear ends 23 of the shoulder straps 18 are connected to the upper shanks of the loops 9 and 9' by suitable eyes 23 through which the shanks are threaded at points intermediate the ends of the shanks. This anchors the shoulder straps to the elastic connection aforesaid, holding the brassière in proper position and yet allowing it to yield as the wearer moves.

To mold the breasts and to correct any abnormal shape pairs 14, 17 and 15, 16 non-elastic bands are secured to the front ends of the shoulder straps 18, the number of these pairs depending upon the size of the breast to be molded, the more pairs being required the larger the breasts are. These bands are arranged like the inverted letter V, being secured at their lower ends to the edges of the cut out portions 4, and their upper ends are secured to the shoulder straps. The upper bands 15 and 16 have extensions 19 and 20 respectively serving to reinforce the supports 2 and 3 at these points.

The shoulder straps 18 extend over the shoulders 21 and over the back 22 in such a manner that the middle portion of the back remains free and their eyes 23, as described are attached to the elastic loops 9, 9' so that the shoulder straps are subjected to a downward elastic pull exerted by the loops 9, 9' anchored to the girdle 12 at 11, as described, and the shoulder straps transmit this pull to the bands 14 to 17 at their front ends. By the slight elastic reaction of the loops, a correspondingly slight lateral pressure is exerted on the curved base lines of the breasts 24, this pressure having the effect to increase the height of the breasts so that the breast nipples 25 are displaced to the sides and a so-called "standing breast" is produced where the bust was formerly flat.

As the elastic loops 9, 9' exert a pull in the direction of the arrows c, d the supports 2 and 3 will fit tightly against the sides of the body and prevent the breasts from yielding laterally.

In the case of two full breasts the number of non-elastic bands is increased so as to produce a uniform distribution as regards the height and diameter.

- 5 It is important that the upper sides of the supports 2, 3 are connected with the shoulder straps by the non-elastic bands 14, 17 and 15, 16 arranged in pairs converging in upward direction and that each support 2, 3 has in the front 10 an aperture 4 allowing the protrusion of the breast nipple and the adjacent portion of the breast. By means of the invention breasts lacking the beautiful and youthful shape can be influenced as regards their size by the elastic re- 15 action transmitted the non-elastic bands by the shoulder straps 18 from the elastic means 9, 9' so that the height of the breast is increased as necessary for producing an aesthetic appearance.

I claim:

In a brassière for supporting and molding the bust, a pair of breast supports connected at their front ends, a pair of shoulder straps, pairs of bands arranged in the shape of the inverted letter V connected to the front end of each shoulder strap at the apex, and to the corresponding supports by their front ends, at the base, and arranged to clear the nipples, a girdle, an elastic member attached to the rear end of one of the 10 supports, means for anchoring this member on the girdle, another elastic member attached to the rear end of the other support and mounted to slide on the anchored member, and means for connecting the rear ends of the shoulder 15 straps to the elastic members at points intermediate the ends of the members.
